UNITED STATES PATENT OFFICE

168,387

MOLDED PLASTIC CONTAINER FOR TIRE VALVE CORES

Selden T. Williams, Belleroose, N. Y., assignor to
Scovill Manufacturing Company, Waterbury,
Conn., a corporation of Connecticut

Application April 16, 1952, Serial No. 19,343

Term of patent 14 years

(Cl. D58—12.6)

To all whom it may concern:

Be it known that I, Selden T. Williams, a citizen of the United States of America, residing at Belleroose, in the county of Nassau and State of New York, have invented a new, original, and ornamental Design for a Moulded Plastic Container for Tire Valve Cores, of which the following is a specification, reference being had to the accompanying drawings forming part thereof, wherein:

Figure 1 is a top plan view of a moulded plastic container for tire valve cores showing my new design.

Fig. 2 is a front elevational view of the container.

Fig. 3 is an end elevational view of the container.

Fig. 4 is a sectional view through the container,

said section being taken along the broken line 4—4 of Fig. 1.

Fig. 5 is a bottom plan view of the container.

I claim:

The ornamental design for a moulded plastic container for the tire valve cores, as shown.

SELDEN T. WILLIAMS.
